Atty.

UNITED STATES PATENT OFFICE.

JAMES B. ROBERTSON, OF BUSHNELL, ILLINOIS.

CHECK-BOOK HOLDER.

1,242,475.

Specification of Letters Patent.

Patented Oct. 9, 1917.

Application filed January 8, 1917. Serial No. 141,178.

To all whom it may concern:

Be it known that I, JAMES B. ROBERTSON, a citizen of the United States, residing at Bushnell, in the county of McDonough and 5 State of Illinois, have invented a new and useful Check-Book Holder, of which the following is a specification.

My present invention relates to covers for holding or containing books or blocks of 10 bank-checks, mileage-books, etc., of the general nature shown in the accompanying drawing and briefly referred to herein, but more fully shown in my co-pending application, filed April 19, 1916, Serial No. 92,116.

15 In the type of check-books and covers therefor just referred to, the checks proper are attached to stubs on which are printed, in several transversely arranged lines, different amounts or sums, or other data. It 20 is desired to sever a portion of each stub without detaching it from the check proper. The principal object of the invention is to provide a cover or holder for the check-book, which cover shall securely but removably 25 hold the book, which shall hold a portion of the cut stubs in reversed position, and which shall include means whereby the stub may be cut transversely in order to leave attached to the check that portion thereof 30 which shall correspond to the amount written by the maker on the face of the check.

In the accompanying drawing I have shown a preferred embodiment of the invention, in which:

35 Figure 1 is a top plan showing the preferred form of holder, and showing also a block or book of blank checks held therein;

Fig. 2, a side or edge view, showing several used stubs as held in reversed position 40 by the novel stub-clip or keeper;

Fig. 3, a perspective of the holder;

Fig. 4, a perspective detail of the cutter, and

Fig. 5, a similar view of the plate with 45 which the stub-lock engages.

Considering the drawings in detail, and referring to each element and, where necessary, to each part thereof by a distinguishing numeral, uniformly employed, 2 denotes 50 an elongated flexible strip made of leather of any other suitable material and comprising the base or back. Secured to one of its end portions, as by stitches 3, is a flap 4 which, being unsecured at both ends, con-

stitutes a sheath which may be utilized not 55 only to retain the tongue 5 of the check-book 6 (presently more fully described) but which is further adapted to hold tickets, bills, checks, cards, or any other thin articles. Each check is shown as comprising a stub 60 portion *c* and a check portion *d*.

The check book *per se*, not claimed herein, is shown as comprising a book or block of checks the stub-portions of which are printed with such inscriptions as "Not over 65 \$5.00", "Not over \$10.00", etc., as shown in Fig. 1, in order that they may be cut off (to prevent raising them) at the proper place, as fully described in my copending application aforesaid, and to the back of 70 each block of checks is secured the tongue 5. In order that the stubs may be severed at the proper place and neatly I provide a cutter 7, L-shaped in cross-section, the larger arm 8 of which is suitably secured, as by 75 gluing, between the strip 2 and a lining 9 stitched thereto at 10, 10.

When the checks and the indicating portion of the stubs have been severed, which may be done by bending the flexible back 2 80 and sometimes the lining 9, it is desirable to leave perfectly free and unobscured the face of the next check and stub. The user will therefore turn or reverse the used stubs back to the position indicated in Fig. 2 and 85 insert them under an arch-shaped swinging stub-keeper 12 which comprises a body portion 13 and terminals 14 offset therefrom but substantially parallel therewith. These terminals seat loosely in apertures 15' in 90 ears 15 bent up from the plate 16 which is held in place between the back 2 and lining 9 by the stitches 10, 10. This form of stub-keeper is much superior to an immovable or rigid one, for when there are a large 95 number of stubs inserted under it its arch swings upward to accommodate them, and when it is not in use or when but a few stubs are held by it, the arch reverses or swings downward and permits the free-end portions of the checks *per se* to lie therein, thus 100 eliminating or avoiding bulkiness.

When not in use the checks *per se* are folded back upon themselves, substantially at the point *a*, and the cutting-end portion 105 of the holder is doubled upon the other endportion, substantially at its midlength *b*, and in order to hold the respective parts

in these positions I provide transversely arranged flaps 18, 19, the former provided with a button 20 and the latter with a spring button-receiver 21, adapted, of course, 5 for engagement.

Considerable variation in the details of this construction, without departing from the spirit of my invention, is possible. Therefore I do not intend to limit myself 10 to the specific form herein shown and described, except where particularly and specifically pointed out in the following claims, wherein it is my intention to claim as broadly as is permitted by the state of the 15 art all the novelty inherent in the invention.

Having thus set forth the construction and operation, the purposes and advantages of my invention, I claim as new the following, to-wit:—

1. A check-book holder comprising a back folded upon itself substantially at its mid-length to form a front and a back, a flap 25 which together with the back forms a sheath, a check-book having a tongue seated in said sheath, each check of the book including a stub, a plate secured to said front, arranged transversely thereof and provided with upstanding ears adapted to prevent 30 lateral movements of the stubs when the latter are reversed, and a keeper mounted in

said ears and adapted to hold the stubs in reversed positions.

2. A check-book holder comprising a base adapted to be folded upon itself, a cutter 35 attached to the end of said base and adapted to sever checks held therein, means hinged at opposite sides of the base, for holding the checks in reversed position, and means for holding the base together when in doubled position.

3. The combination with a block of checks and a securing-tongue attached to one end portion of the back, of a holder including a back, an element secured thereto and together with said back forming a sheath in which said tongue seats, a cutter arranged at the other end of the back, and a stub-keeper arranged intermediate the tongue-securing element and said cutter.

4. A check-book holder including a sheath adapted to be engaged by a tongue-like projection from the back of a check-book, a cutter for severing the checks, arranged remote from the sheath, a hinged 55 stub-keeper arranged intermediate said sheath and cutter, a pair of securing-flaps extending transversely of the longitudinal line of the holder.

In testimony whereof I hereunto set my hand this 3rd day of January, 1917.

JAMES B. ROBERTSON.
